AIR DISTRIBUTING MEANS FOR AIR
CONDITIONING APPARATUSAndrew A. Kucher, Dayton, Ohio, assignor to
General Motors Corporation, Dayton, Ohio, a
corporation of Delaware

Application September 20, 1939, Serial No. 295,793

3 Claims. (Cl. 98—33)

This invention relates to air distributing means for air conditioning apparatus and more particularly to air conditioning apparatus which may be installed in existing buildings without materially altering the existing building structure.

One object of this invention is to provide an improved air distributing duct system.

Another object of this invention is to provide air ducts which are inexpensive to manufacture and install.

Another object of this invention is to provide air ducts adapted to be threaded or snaked through hollow walls, around corners, etc.

Still another object of this invention is to provide a system of ducts for distributing conditioned air in proper amounts to the proper places without producing objectionable noises.

Still another object of this invention is to provide a system of air ducts for conveying conditioned air from the conditioning unit to various parts of the building without the transmission of noise from the conditioning unit to the conditioned spaces.

Further objects and advantages of the present invention will be apparent from the following description, reference being had to the accompanying drawings, wherein a preferred form of the present invention is clearly shown.

In the drawings:

Fig. 1 is a diagrammatic cross-sectional view showing a building provided with an air conditioning system embodying one form of my invention;

Fig. 2 is a diagrammatic view showing a modified form of conditioning system applied to a building which originally was provided with pipes for supplying hot air to the rooms of the building;

Fig. 3 is a fragmentary sectional view, on an enlarged scale, showing the manner in which flexible air ducts constructed in accordance with my invention are installed;

Fig. 4 is a fragmentary sectional view, on an enlarged scale, showing the arrangement at the discharge end of a flexible air duct;

Fig. 5 is a fragmentary sectional view, on an enlarged scale, showing a damper for controlling the amount of air supplied to a flexible air duct; and

Fig. 6 is a fragmentary sectional view taken on the line 6—6 of Fig. 2.

Notwithstanding the fact that vast sums of money have been spent in designing and promoting the sale of air conditioning apparatus for use in private homes and similar installations, the acceptance by the public of central air conditioning plants for use in private homes and similar installations has very greatly lagged behind the acceptance of air conditioning systems

for large auditoriums, restaurants, and the like. One of the principal reasons why central air conditioning systems have not gone into extensive use for private homes and the like is that the cost of an air conditioning system for a home has been in the neighborhood of \$2,000, and much of this cost has been necessitated by the cost of providing air conditioning ducts leading from the central conditioning unit to the various rooms or offices to be conditioned. In many cases the cost of the duct system alone has not been the main objection, as some people have been willing to pay the necessary price; but these people have not been willing to put up with the inconvenience and reconstruction necessitated by the installation of the conventional air ducts. One purpose of this invention, therefore, is to provide air ducts which are inexpensive and which may be readily installed in existing homes or buildings without the necessity of excessive cutting of walls or damage to the decorative surfaces.

Referring now to Fig. 1 of the drawings, there is shown a building 10 having a plurality of rooms 11 adapted to be conditioned, and a machine room 12 which, for purposes of illustration, has been shown as located in the basement of the building. The reference numeral 14 designates an air conditioning unit comprising an evaporator 16 and a heating unit 18 over which air to be conditioned is circulated by means of the blower 20 operated by a motor 22. The heating and cooling units may be of any suitable type. As shown, the evaporator may be supplied with volatile refrigerant by means of conventional liquefying system 24. The air to be conditioned enters the conditioning unit 14 through a plurality of flexible return air ducts 26. The conditioned air is distributed to the rooms through a plurality of ducts 28 which lead from the conditioning unit to the various rooms, as shown in the drawings. Each of the air ducts 26 and 28 consists of a small diameter flexible tube member which is adapted to pass between the walls of the building as shown. These ducts have sufficient flexibility to permit short bends without material distortion of the cross section. The ducts are of the proper diameter to permit them to be installed between the walls of existing structures, and are sufficiently flexible so as to permit the ducts to be fed through the wall sections to desirable outlet positions. Inasmuch as the ducts are thus flexible they may readily pass between plastered wall sections and around obstructions such as are frequently found in buildings. Inasmuch as the ducts are of small diameter so as to facilitate installation, the air is delivered into the ducts at a relatively high pressure and discharges from the duct at a relative high velocity. In order to largely eliminate drafts

and objectionable noises, the discharge openings of the ducts are provided with suitable air directing and diffusing means, such as at 30, shown on an enlarged scale in Fig. 4. In view of the low cost of the ducts and the ease with which the ducts may be installed, each room may be provided with a plurality of air supply ducts, if necessary. For the purpose of illustration, however, I have shown only one supply duct per room.

As shown in Figs. 1, 2 and 3, the air ducts are installed by cutting a hole 32 in the plastered wall through which a flexible wire 34 or the like is threaded and thereafter secured to a cap member 36 attached to the end 38 of the duct. After securing the wire 34 to the cap 36, the wire and duct are pulled up through the wall. The upper end of the duct 38 is thereafter secured to a flexible hood 30 which is constructed in such a manner as to efficiently diffuse the air and at the same time silence the air flow. The hood 30 is made of felt or some similar material. Sound deadening material 40 may be provided in the upper corner of the hood 30. It has been found that with this duct and hood construction the high velocity air may be discharged from the opening 32 without any objectionable noise. Rather than providing each air duct with a butterfly damper mounted in the duct, I have provided a special damper arrangement for controlling the amount of air flowing in each duct.

As best shown in Fig. 5 a damper 44 is carried by a pin 46 which is slidably mounted in a bushing 48 preferably carried by the wall of the conditioning unit. A knob 51 is provided for adjusting the setting of the damper so as to vary the amount of air flowing into the duct. The arrangement shown in Fig. 1 is the arrangement which would be installed in existing buildings in which no hot air ducts have ever been provided or in which the old hot air ducts are for some reason or other unsuitable for use. In Fig. 2 I have shown a very similar arrangement except that the existing hot air ducts 50 have been converted into return air ducts thereby avoiding the necessity of providing new return air ducts. Inasmuch as the flexible air ducts are considerably smaller than those previously used, it is possible to arrange the flexible air supply duct so as to pass within the return air duct in installations in which the old hot air duct is utilized for the return air duct.

In Fig. 6, for example, I have shown such an arrangement in which a flexible air supply duct 28 has been inserted directly within one of the metallic return air ducts 50 which was previously used as a hot air duct. Inasmuch as the usual practice has been to arrange a hot air register in the wall of the room adjacent the floor or directly in the floor of the room, the flexible air duct which supplies the air to the room is extended beyond the opening 52 to an opening 54 provided adjacent the ceiling. With such an arrangement the conditioned air is supplied to the room from a point adjacent the ceiling and the recirculated air is withdrawn from a point adjacent the floor of the room. By virtue of my improved construction and arrangement the cost of air conditioning units of this general type has been greatly reduced and the inconvenience resulting from the cutting of walls, floors, etc., has almost been eliminated without sacrificing efficiency. Furthermore, the time required for installing a system of this type has also been very materially reduced, as the time required for cutting the outlet open- 75

ings in the wall and for threading the flexible ducts up into the rooms is much less than the time required for installing the old type of air ducts. This is an important advantage as the occupants of a building are not put to any inconvenience for any length of time.

As illustrated in Fig. 5, the flexible duct comprises a spiral reinforcing element 60, and the outer surface of the duct is provided with a spiral groove 61. By virtue of the spiral groove on the outer surface of the duct, it is possible to screw the duct in place into the wall of the air conditioning unit 14 by slightly offsetting the sheet metal adjacent the duct opening, as shown at 62 in Fig. 5.

While the form of embodiment of the invention as herein disclosed, constitutes a preferred form, it is to be understood that other forms might be adopted, all coming within the scope of the claims which follow.

What is claimed is as follows:

1. Air conditioning and distributing apparatus adapted for installation in existing hollow wall buildings having a plurality of rooms to be conditioned comprising in combination, a central air conditioning unit, a conditioned air outlet in each room, means for conveying high velocity conditioned air from said unit through the hollow walls to each of said outlets, each of said last named means comprising a substantially circular flexible duct means adapted to be snaked from said unit through the hollow portion of the walls of said building to one of said outlets, and sound deadening means within the hollow portion of said wall adjacent said air outlet comprising a non-metallic end cap having an opening communicating with said outlet and having an upper inner corner extending beyond the upper edge of said opening and containing sound deadening material and having a lower opening communicating with the upper end of the duct, the upper wall of said end cap sloping downwardly from said corner toward the outlet.

2. Air conditioning and distributing apparatus comprising in combination, an air conditioning unit, a conditioned air outlet, means for conveying high velocity conditioned air from said unit to said outlet comprising an air duct having its outlet end arranged substantially at right angles to the plane of said outlet, a non-metallic end cap closing the upper end of said duct and having an opening communicating with said outlet and having an upper inner corner extending above the upper edge of said opening and having an upper wall sloping downwardly from said corner toward said opening and having a lower opening communicating with the upper end of said air duct.

3. Air conditioning and distributing apparatus comprising in combination, an air conditioning unit, a conditioned air outlet, means for conveying high velocity conditioned air from said unit to said outlet comprising an air duct having its outlet end arranged substantially at right angles to the plane of said outlet, a non-metallic end cap closing the upper end of said duct, and having an opening communicating with said outlet and having an upper inner corner extending above the upper edge of said opening and having an upper wall sloping downwardly from said corner toward said opening and having a lower opening communicating with the upper end of said air duct, and sound deadening material disposed within said end cap.

ANDREW A. KUCHER.
